UNITED STATES PATENT OFFICE.

THOMAS McC. SALE, OF MORGANFIELD, KENTUCKY.

BED-SLAT CLAMP.

SPECIFICATION forming part of Letters Patent No. 288,668, dated November 20, 1883.

Application filed March 22, 1883. (No model.)

to all whom it may concern:

Be it known that I, THOMAS McC. SALE, of Morganfield, in the county of Union and State of Kentucky, have invented certain new and useful Improvements in Bed-Slat Clamps; and I do hereby declare the following to be a full, clear, and exact description of the invention, such as will enable others skilled in the art to which it pertains to make and use it, reference 5 being had to the accompanying drawings, which form part of this specification.

My invention relates to an improvement in bed-slat clamps; and it consists in the combination of the side rail of the bed, having a catch 15 secured to its inner side opposite the end of each slat, with a flanged clamp which is secured to one end of each slat, or those slats that are too short to always remain in position when a weight is applied to them, as will be 20 more fully described hereinafter.

The object of my invention is to provide the bed-slats with a suitable attachment which will prevent their ends from sliding off of the side rails of the bed whenever a weight or 25 pressure is applied to them, and thus prevent slats which are a little short from constantly dropping out of place.

Figure 1 is a plan view of my invention. Fig. 2 is a vertical cross-section of the same.

30 A represents a side rail of the bed and B a slat. Secured to the inner side of the rail opposite each slat, or, if so preferred, only opposite those slats which are too short, is a suitable catch, C, which may be of the shape here 35 shown.

Secured to each one of the slats, or, if preferred, only to those slats which are too short to remain in place when pressure is applied thereto, is the clamp D, which is held in place by a set-screw, F, and which has the flange G formed 40 upon its inner end. The flange of this clamp is made to drop down inside of the catch, and thus prevent the end of the slat from slipping off from the side rail and dropping upon the floor.

45 One great trouble with bed-slats has been that where they are not made abundantly long any great pressure or any sudden pressure brought to bear upon them will cause them to bend downward, and one or both of their ends 50 then slip from their side rails upon the floor. Where the slats are short this is a constant source of trouble and vexation. By means of the appliance here shown the slats, however 55 short, as long as their ends can be made to catch securely in the clamp and the flange upon the clamp drop down inside of the catch, can be made to answer every purpose.

Having thus described my invention, I claim—

60 The combination of the side rail, the slat, the catch, the flanged clamp, and a set-screw for holding the clamp in place, substantially as described.

In testimony whereof I affix my signature in presence of two witnesses.

65 THOMAS McCAJARH SALE.
